(57) **CLAIM**

The ornamental design for a chair, as shown and described.

DESCRIPTION

FIG. 1 is a perspective view of the chair;

FIG. 2 is a front elevational view of the chair;

FIG. 3 is a rear elevational view of the chair;

FIG. 4 is a left side elevational view of the chair, the opposite side of which is a mirror image;

FIG. 5 is a top plan view of the chair; and,

FIG. 6 is a bottom plan view of the chair.

The broken lines shown in the drawings illustrate portions of the chair, which form no part of the claimed design.
